INVENTOR
Frederick W. Martin.

by Edward Wright, Atty.

UNITED STATES PATENT OFFICE.

FREDERICK W. MARTIN, OF NEW YORK, N. Y., ASSIGNOR TO FRANKLIN RAILWAY SUPPLY COMPANY, OF WILMINGTON, DELAWARE, A CORPORATION OF DELAWARE.

AUTOMATIC WEDGE FOR DRIVING-BOXES.

1,268,746.

Specification of Letters Patent.

Patented June 4, 1918.

Application filed September 1, 1917. Serial No. 189,293.

To all whom it may concern:

Be it known that I, FREDERICK W. MARTIN, of the borough of Queens, in the county of Queens, city and State of New York, have 5 invented a certain new and useful Improvement in Automatic Wedges for Driving- Boxes, of which improvement the following is a specification.

This invention relates to the adjustable 10 mounting of the driving axle-box in the frame or pedestal of locomotives.

In the standard construction as heretofore used the driving-box is provided with flanges extending upon opposite sides of the 15 pedestal jaws, and between the box and the jaw at one side is located a wedge or wedges for automatically taking up the wear between the driving-box and frame, the wedge being formed with flanges also extending 20 upon both front and rear sides of the pedestal jaw. A wear shoe having like flanges has also been used at the opposite side of the driving-box. Some trouble has been experienced with this form of automatic 25 wedge on account of the breaking of the flanges which necessitates a replacement by an tire new wedge or shoe.

The object of my invention is to eliminate the flanges from the wedges or shoes, and 30 provide instead, independent removable wear strips bolted or riveted to the inner and outer sides of the pedestal jaw, the strips extending beyond the bearing face of the pedestal jaw and serving as guides for 35 the wedge or wedges.

In the accompanying drawings; Figure 1 is a side elevation, with one half of the driving-box and wedges indicated in section; Fig. 2 a horizontal section taken on the 40 line 2—2 of Fig. 1, and Fig. 3 a similar section showing a modification.

According to the construction shown the locomotive frame is formed with the usual 45 pedestal jaws 4 and 5, between which is mounted the driving axle-box 6, having flanges 7 and 8. The jaw 4 at one side is formed with an inclined face for co-operating with the automatic wedge or wedges

located between said inclined face of the pedestal jaw and the driving-box. Two 50 such wedges are shown in the drawing, the adjusting wedge 9, engaging the pedestal, and the floating wedge 10, bearing against a surface on the driving-box which may also be slightly inclined. According to my im- 55 provement separate wear strips 11, are removably attached to the inner and outer sides of the pedestal, preferably by bolts or rivets, and extend beyond the face of the jaw for the purpose of guiding the wedge 9. 60 The floating wedge 10, may extend the full width between the flanges of the driving- box, as shown in Fig. 2, or it may be of the same width as the adjusting wedge 9, and the wear strips 11 may be extended at the 65 sides of both wedges to guide the same, as indicated in Fig. 3.

The adjusting wedge is actuated by the spring 12 and operates in the usual way to automatically take up the wear between the 70 driving-box and pedestal.

The improved wear strips not only serve as a guide for the wedge but also stiffen the connection between the pedestal and driving-box and take the wear of the driv- 75 ing-box flanges. When any one of these strips becomes worn or broken it may be readily removed and replaced without renewing the wedges. By the use of these independent wear strips they may be made 80 of steel or of different metal from the wedges and thereby increase the durability and strength of the construction.

Having now described my invention, what I claim as new and desire to secure by Letters Patent is:

1. The combination with a driving-box pedestal, of a wedge of substantially the same width as the thickness of the pedestal jaw, and removable wear strips attached to 90 the front and rear sides of the pedestal and extending upon opposite sides of the wedge to guide the same.

2. The combination with a pedestal, a driving-box having flanges, and a wedge for 95 taking up wear, of removable wear strips

attached to the front and rear sides of the pedestal and extending between the sides of the wedge and the flanges of the driving-box.

3. The combination with a pedestal, and
5 a driving-box having flanges, of an adjusting wedge of substantially the same width as the thickness of the pedestal, a floating wedge extending between the flanges of the

driving-box, and removable wear strips attached to the sides of the pedestal and extending upon opposite sides of the adjusting wedge. 10

In testimony whereof I have hereunto set my hand.

FREDERICK W. MARTIN.
